UNITED STATES PATENT OFFICE

NORMAN P. HARSHBERGER, OF SCARSDALE, NEW YORK

ROOFING AND SIDING ELEMENT

Application filed May 26, 1930. Serial No. 455,841.

This invention relates to improvements in roofing and siding elements and is a continuation in part of my Patent Number 1,759,901, dated May 27, 1930.

5 It is one of the objects of this invention to provide an improved roofing and siding element having tabs which are constructed in a novel shape to provide relatively wide sections for overlapping the nails extending 10 through an element below so as to amply cover the holes formed by said nails to prevent rain or moisture from working thereinto and to effectively cover and protect the abutting ends of two adjacent shingles in the 15 course below.

A further object of this invention is to provide a roofing and siding element having tabs with relatively wide lower edges so that when the elements are laid on a roof and are viewed 20 edgewise there will be relatively long portions of double thickness.

A more specific object of this invention is to provide a roofing and siding element in which the tabs are of greater width at their 25 lower edges than at the point where they join the body portion.

A further object of this invention is to provide a roofing and siding element which, when laid with other elements on the roof, 30 will form a plurality of symmetrical figures to make a pleasing impression upon the eye.

A further object of this invention is to provide a roofing and siding element which is simple in construction, which can be 35 economically cut from a blank and which is well adapted for the purposes described.

With the above and other objects in view, the invention consists of the improved roofing and siding elements and its parts and 40 combinations as set forth in the claims and all equivalents thereof.

In the accompanying drawing, illustrating 45 one complete embodiment of the invention, in which the same reference characters designate the same parts in all of the views:

Fig. 1 is a plan view of a sheet of roofing material showing the method of cutting out the improved elements;

50 Fig. 2 is a plan view of one of the elements; and

Fig. 3 is a plan view of a group of said elements as they appear when assembled upon a roof.

Referring to the drawing the shingles are 55 preferably formed from a sheet 5 of the usual composition material. Said sheet is cut longitudinally along the line 6 to form alternating tabs and recesses of elements to be cut from each side of the sheet. The sheet is then cut transversely along lines 7 which extend inwardly from each side and only 60 partially across the sheet. The lines 7 may be spaced any distance apart according to the number of units which it is desired to form in one strip.

65 The completed element shown in Fig. 2 comprises a body portion 8 which is substantially rectangular in shape. The exact shape of the body, however, may be varied as desired. Said body portion has depending 70 from its lower edge spaced apart tabs 9. The sides 10 of said tabs are diverging so that the lower edge 11 is of greater length than the upper edge of the tabs where they connect with the body. Between each pair of tabs, 75 recesses 12 are formed, the said recesses being complementary in shape to the tabs.

In assembly the elements are laid one above another as shown in Fig. 3 with the lower edges 11 of the tabs registering with the upper edges 12 of the recesses. Nails 13 are inserted near the lower edge of the body portion at points midway between two tabs and at points adjacent the ends of each element. Said last mentioned points are also substantially midway between two tabs when another element is placed in the same row. Said 80 nails are covered over by the tabs of an element in the row above. By providing tabs with wide lower edges the nails are positioned 85 farther away from the corners of the tabs than is the case in shingles where the tabs have converging sides to form narrow lower portions. Thus the nail holes are more thoroughly protected from rain and moisture 90 working into the same and the abutting ends of two elements in the same course are effectively protected as at 14, the outwardly diverging sides of the tabs providing a greater 95 width of coverage and serving to direct rain 100

and the like away from the joint at the abutting ends. It is further to be noted that when a group of elements is viewed edgewise that there are long portions of double thickness formed by the lower edge of a tab and the edge of a recess. These portions of double thickness are rendered longer than usual due to the peculiar shape of the tabs. The finished roof will present a group of four-sided figures in which one pair of opposite sides is V-shaped, the apexes of said sides extending toward one another.

Although only one form of the invention has been shown and described, it is not deemed to be limited to this exact showing, as the broad concept of the invention includes all changes and modifications as may fairly come within the scope of the claims.

What I claim is:

- 20 1. Shingle elements assembled on a roof in overlapping courses, each course having alternating depending tabs and recesses, the recesses being complementary in shape to the tabs, and each course comprising a plurality of separate elements having end extensions which abut one another, the lower edges of said abutting end extensions forming the bases of some of the recesses, said tabs having their lower edges of greater length than the upper portions of the tabs and said lower edges being of substantially the same length as the bases of the recesses, certain of the tabs being positioned over the abutting ends of two elements in the course below to protect the joint formed by said ends.
- 25 2. Shingle elements assembled on a roof in overlapping courses, each course having alternating depending tabs and recesses, the recesses being complementary in shape to the tabs, and each course comprising a plurality of separate elements having end extensions which abut one another, the lower edges of said abutting end extensions forming the bases of some of the recesses, said tabs having a pair of straight downwardly diverging side edges and a straight bottom edge connecting said side edges to form a dovetail projection, the said bottom edge being of substantially the same length as the bases of the recesses, certain of the tabs being positioned over the abutting ends of two elements in the course below to protect the joint formed by said ends, the diverging side edges directing rain away from the joint.
- 30 3. Shingle elements assembled on a roof in overlapping courses, each course having alternating depending tabs and recesses, the recesses being complementary in shape to the tabs, and each course comprising a plurality of separate elements having end extensions which abut one another, the lower edges of said abutting end extensions forming the bases of some of the recesses, said tabs having their lower edges straight and of greater length than the upper portions of the tabs and said lower edges being of substantially the same length as the bases of the recesses, certain of the tabs being positioned over the abutting ends of two elements in the course below to protect the joint formed by said ends.
- 35 4. Shingle elements assembled on a roof in overlapping courses, each course having alternating depending tabs and recesses, the recesses being complementary in shape to the tabs, and each course comprising a plurality of separate elements having end extensions which abut one another, the lower edges of said abutting end extensions forming the bases of some of the recesses, said tabs having their lower edges of greater length than the upper portions of the tabs and said lower edges being of substantially the same length as the bases of the recesses, certain of the tabs being positioned over the abutting ends of two elements in the course below to protect the joint formed by said ends.

- 40 5. Shingle elements assembled on a roof in overlapping courses, each course having alternating depending tabs and recesses, the recesses being complementary in shape to the tabs, and each course comprising a plurality of separate elements having end extensions which abut one another, the lower edges of said abutting end extensions forming the bases of some of the recesses, said tabs having their lower edges of greater length than the upper portions of the tabs and said lower edges being of substantially the same length as the bases of the recesses, certain of the tabs being positioned over the adjacent ends of two elements in the course below to protect the joint formed by said ends.
- 45 6. Shingle elements assembled on a roof in overlapped courses, each course having alternating depending tabs and recesses, the recesses being complementary in shape to the tabs, and each course comprising a plurality of separate elements having end extensions adjacent one another, the lower edges of said adjacent end extensions forming the bases of some of the recesses, said tabs having their lower edges of greater length than the upper portions of the tabs and said lower edges being of substantially the same length as the bases of the recesses, certain of the tabs being positioned over the adjacent ends of two elements in the course below to protect the joint formed by said ends.
- 50 7. Shingle strips assembled on a roof in overlapping courses, each strip having a plurality of alternating depending tabs and recesses, the recesses being complementary in shape to the tabs, said strips having end extensions adjacent one another, the lower edges of said adjacent end extensions cooperating to form the bases of some of the re-

certain of the tabs being positioned over the abutting ends of two elements in the course below to protect the joint formed by said ends, the lower edges of the tabs substantially aligning with the bases of the recesses.

70 4. Shingle elements assembled on a roof in overlapping courses, each course having alternating depending tabs and recesses, the recesses being complementary in shape to the tabs and the latter having downwardly diverging sides, each course comprising a plurality of separate elements having end extensions which abut one another, the lower edges of said abutting end extensions forming the bases of some of the recesses and the lower edges of the tabs being of substantially the same length as the bases of the recesses, certain of the tabs being positioned over the abutting ends of two elements in the course below to protect the joint formed by said ends and the diverging sides of the tabs directing rain and the like away from said joint.

75 5. Shingle elements assembled on a roof in overlapping courses, each course having alternating depending tabs and recesses, the recesses being complementary in shape to the tabs and each course comprising a plurality of separate elements having end extensions which abut one another, the lower edges of said abutting end extensions forming bases of some of the recesses, said tabs having a pair of straight downwardly diverging side edges and a straight bottom edge connecting said side edges to form a dovetail projection, the said bottom edge being of substantially the same length as the bases of the recesses, certain of the tabs being positioned over the abutting ends of two elements in the course below to protect the joint formed by said ends, the diverging side edges directing rain away from the joint.

80 6. Shingle elements assembled on a roof in overlapped courses, each course having alternating depending tabs and recesses, the recesses being complementary in shape to the tabs, and each course comprising a plurality of separate elements having end extensions adjacent one another, the lower edges of said adjacent end extensions forming the bases of some of the recesses, said tabs having their lower edges of greater length than the upper portions of the tabs and said lower edges being of substantially the same length as the bases of the recesses, certain of the tabs being positioned over the adjacent ends of two elements in the course below to protect the joint formed by said ends.

85 7. Shingle strips assembled on a roof in overlapping courses, each strip having a plurality of alternating depending tabs and recesses, the recesses being complementary in shape to the tabs, said strips having end extensions adjacent one another, the lower edges of said adjacent end extensions cooperating to form the bases of some of the re-

cesses between tabs in each course, said tabs having their lower edges of greater length than the upper portions of the tabs and said lower edges being of substantially the same length as the bases of the recesses, certain of the tabs being positioned over the adjacent ends of the two strips in the course below to protect the joint formed by said ends.

8. Shingle strips assembled on a roof in overlapping courses, each strip having a plurality of alternating depending tabs and recesses, the recesses being complementary in shape to the tabs, and said strips having end extensions adjacent one another, the lower edges of said adjacent end extensions cooperating to form the bases of some of the recesses between tabs in each course, said tabs having their lower edges of greater length than the upper portions of the tabs, said lower edges wholly overlying the body portion of the strips of a course below and being of substantially the same length as the bases of the recesses, certain of the tabs being positioned over the adjacent ends of the two strips in the course below to protect the joint formed by said ends.

In testimony whereof I affix my signature.
NORMAN P. HARSHBERGER.
